(57) **CLAIM**

The ornamental design for a knife insert for drawer, as shown and described.

DESCRIPTION

FIG. 1 is a top, front, right side perspective view of a knife insert for drawer showing our new design;

FIG. 2 is a right side elevational view thereof;

FIG. 3 is a left side elevational view thereof;

FIG. 4 is a top view thereof;

FIG. 5 is a bottom view thereof;

FIG. 6 is a front view thereof; and,

FIG. 7 is a back view thereof.

The broken line portions are included to show unclaimed subject matter only and form no part of the claimed design.
